CAR CONSTRUCTION

Frank Ditchfield, Cleveland, Ohio, assignor to
 The Youngstown Steel Door Company, Cleve-
 land, Ohio, a corporation of Ohio

Application March 4, 1941, Serial No. 381,711

9 Claims. (Cl. 105—409)

This invention relates to railway car construction and more specifically to a metallic side wall structure applicable as a unit in the conversion of cars to metallic house cars and in the construction of new metallic house cars.

It is an object of this invention to provide metallic side wall structures for house cars embodying posts, means for directly connecting the posts and car underframes and bottom longitudinally extending members which shall be of uniform width regardless of width of car underframe and inside width of car.

A further object is to provide metallic side wall structures for house cars embodying posts, means for directly connecting the posts and car underframes and bottom longitudinally extending members, the connecting means being so constructed and positioned as to serve as supports for floor boards.

A further object is to provide metallic side wall structures for house cars embodying posts, means for directly connecting the posts and car underframes and bottom longitudinally extending members, these members being associated with the connecting means to resist the pull of the posts independently of the means fastening the members and the connecting means together.

A further object is to provide metallic side wall structures for house cars embodying posts, means for directly connecting the posts and car underframes and bottom longitudinally extending members, the connecting means and longitudinally extending members serving to support the floor boards.

A further object is to provide metallic side wall structures for house cars embodying posts, means for directly connecting the posts and the car underframes and bottom longitudinally extending members which shall be of uniform width regardless of width of car underframe and inside width of car and characterized further by a reduction in the number of connecting means employed.

A further object is to provide metallic side wall structures for house cars embodying posts, means for directly connecting the posts and car underframes and bottom longitudinally extending members which shall be of uniform width wherein said structures shall serve as load carrying girders of standard construction regardless of width of underframe and inside width of car.

Other objects of the invention will become clear as the description thereof proceeds.

In the drawings forming part of this specification:

Fig. 1 is an elevation showing a metallic car side wall structure embodying the invention, parts being broken away to permit illustration on a larger scale.

5 Fig. 2 is a vertical section taken on line 2—2 of Fig. 1.

Fig. 3 is a vertical section taken on line 3—3 of Fig. 2.

In the embodiment of the invention illustrated 10 in the drawings the side wall unit is designated in its entirety by the reference numeral 10. It will be apparent that in this figure only a portion of a side wall unit is illustrated which extends from the door opening to one end of the car. 15 The other portion of the unit is of similar construction and it will be understood that the unit for the opposite side of the car will embody the construction illustrated.

The side wall unit 10 includes a side plate 11 which, as is customary, extends substantially from end to end of the car. The side plate is preferably Z-shaped in section. To it are secured the upper ends of the door posts 12 and intermediate posts 13 which also are preferably 25 Z-shaped in section. The securing of the upper ends of these posts to the side plate is effected by means of brackets 14 in the manner more clearly shown in applicant's co-pending application, Serial No. 167,739, filed October 7, 1937, 30 which has matured into Patent 2,235,449, granted March 18, 1941. As is customary, the door post is arranged with the web 15 thereof parallel to the wall and the flanges 16 and 17 extending respectively outwardly and inwardly at right angles to the wall. The intermediate posts 13 are arranged with their webs 18 at right angles to the wall and their flanges 19 and 20 parallel to the wall.

Metallic sheathing 21 is secured along its upper 35 margin to the side plate 11 and to the outside of the door posts and intermediate posts. The sheathing is composed preferably of a plurality of sections which overlap at posts as is well understood.

The side wall structure 10 embodies a bottom longitudinally extending member 22 the length of which is preferably equal substantially to the length of the structure. As more clearly illustrated in Fig. 2 of the drawings, the longitudinally extending member 22 is preferably in the form of an angle disposed with one leg 23 vertical and the other leg 24 horizontal. The vertical leg 23 extends upwardly relatively to the horizontal leg 24 and is secured as by means of rivets 50 25 and 26 to the lower ends of the door and

intermediate posts and to the lower margin of the metallic sheathing. The horizontal leg 24 is disposed below the lower ends of the posts so as to provide space for the reception of the outer sections of brackets utilized to secure the posts to the underframe of the cars to which the side wall structures are applied.

Each of these brackets embodies a vertical flange 27 by means of which the bracket is secured to the car underframe represented in Fig. 2 of the drawings by the side sill 28. A horizontal flange 29 extends outwardly from the upper end of the vertical attaching flange 27 and is reinforced by means of a web 30 projecting outwardly from the vertical flange 27. Beyond the web 30 at the upper portion of the bracket is an outer section 31 preferably rectangular in cross section and cored out as indicated at 32 and 33 in order to reduce the weight of the brackets. The outer section 31 is provided with oppositely extending ears 34 and 35. By reference to Figs. 2 and 3 of the drawings it will clearly appear that the horizontal leg 24 of the longitudinally extending bottom member 22 lies below and in vertically overlapping relationship with the outwardly extending sections of the brackets. Attachment of this flange to the ears 34 and 35 of the brackets may be made if desired. Rivets 36 and 37 are illustrated for this purpose.

The outwardly extending section 31 of each bracket is provided with one or more integral upstanding flanges 38. These flanges are adapted to abut the inwardly extending flange 17 of the door posts or the webs of the intermediate posts and to be secured thereto as by means of rivets 39 and 40. These flanges are reinforced by means of the webs 41.

As more clearly shown in Figs. 2 and 3 of the drawings the horizontal flange 29 and the outer section 31 of the brackets are aligned with the upper surface of the underframe. This flange and the outer section of each of the brackets are accordingly adapted to support a portion of the car floor 42 which extends outwardly beyond the underframe. Support for the outwardly extending portion of the car floor is also provided by the horizontal leg 24 of the bottom longitudinally extending member 22. For this purpose the horizontal leg 24 carries fillers 43, preferably of wood, extending between the outer sections of the brackets.

It will be observed that the side plate, the posts, metallic sheathing and bottom member 22 are disposed in outwardly spaced relationship to the car underframe. By this arrangement an increase in the inside width of the car is obtained both in new car construction and in the conversion of wooden sheathed cars to all steel cars. The bottom longitudinally extending member 22 is spaced from the underframe and the spacing desired is determined by the size of the brackets. Accordingly the longitudinally extending member 22 may be made standard and utilized in railway house cars irrespective of the inside width of the cars and the width of the underframe. This member can, therefore, be a rolled shaped. A standard side wall structure, whether pre-assembled as a unit, or applied in parts, is made possible since it is not affected by variations in widths of car. The side wall structure constitutes a girder effective to carry a portion of the load imposed on the underframe between the bolsters.

It will be observed that all of the rivets securing the brackets and the longitudinally extending member to the posts are in shear and the rivets

fastening the brackets to the car underframe are in shear. The horizontal leg 24 of the bottom member lies below the outer section of each bracket. The entire strength of this leg is consequently effective to resist the upward pull of the posts and of the metallic sheathing intermediate the posts. The rivets 36 and 37 which fasten the horizontal leg 24 to the ears of the outer sections of the bracket are not necessary to develop the strength of the horizontal leg and are utilized merely to prevent shifting of the brackets relative to the bottom longitudinally extending member when the wall structure is shipped as a unit. These rivets may be omitted if desired.

It will be clear, moreover, that the considered structure provides for direct connection between the posts and the car underframe while maintaining the integrity of the section of the horizontal leg 24 of the bottom member 22.

This application is an improvement upon applicant's co-pending application identified herein.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A railway house car comprising a metallic underframe, a metallic side plate, metallic posts secured to said side plate, metallic sheathing secured to said side plate and posts, said side plate, posts and sheathing being spaced outwardly of said underframe, brackets secured to the lower ends of said posts, said brackets extending inwardly from said posts to said underframe and being secured thereto, and a longitudinally extending member spaced outwardly of said underframe and having a horizontal flange disposed below and in vertically overlapping engagement with said brackets, said member having an upstanding flange fastened to said posts and the lower margin of said sheathing.

2. A railway house car comprising a metallic underframe, a metallic side plate, metallic posts secured to said side plate, metallic sheathing secured to said side plate and posts, said side plate, posts and sheathing being spaced outwardly of said underframe, brackets secured to the lower ends of said posts, said brackets extending inwardly from said posts to said underframe and being secured thereto, a longitudinally extending member spaced outwardly of said underframe and having a horizontal flange disposed below and in vertically overlapping engagement with said brackets, said member having an upstanding flange fastened to said posts and the lower margin of said sheathing, and a floor extending outwardly beyond said underframe, said brackets supporting portions of said floor extension.

3. A railway house car comprising a metallic underframe, a metallic side plate, metallic posts secured to said side plate, metallic sheathing secured to said side plate and posts, said side plate, posts and sheathing being spaced outwardly of said underframe, brackets secured to the lower ends of said posts, said brackets extending inwardly from said posts to said underframe and being secured thereto, a longitudinally extending member spaced outwardly of said underframe and having a horizontal flange disposed below and in vertically overlapping engagement with said brackets, said member having an upstanding flange fastened to said posts and the lower margin

of said sheathing, filler members carried by the horizontal flange of said member between said brackets and a floor extending outwardly beyond said underframe, said floor extension being supported upon said brackets and said fillers.

4. A railway house car comprising a metallic underframe, a metallic side plate, metallic posts secured to said side plate, metallic sheathing secured to said side plate and posts, said side plate, posts and sheathing being spaced outwardly of said underframe, brackets secured to the lower ends of said posts, said brackets extending inwardly from said posts to said underframe and being secured thereto, and a longitudinally extending member spaced outwardly of said underframe and having a horizontal flange disposed below and in vertically overlapping engagement with said brackets, said member having an upstanding flange fastened to said posts and the lower margin of said sheathing, said longitudinally extending member being of the same width for varying inside widths of car.

5. A railway house car comprising a metallic underframe, a metallic side plate, metallic posts secured to said side plate, metallic sheathing secured to said side plate and posts, said side plate, posts and sheathing being spaced outwardly of said underframe, brackets secured to the lower ends of said posts, said brackets extending inwardly from said posts to said underframe and being secured thereto, and a longitudinally extending member spaced outwardly of said underframe and having a horizontal flange disposed below and in vertically overlapping engagement with said brackets, said member having an upstanding flange fastened to said posts and the lower margin of said sheathing, said longitudinally extending member being of the same width for varying inside widths of car.

6. A railway house car comprising a metallic underframe, a metallic side plate, metallic posts secured to said side plate, metallic sheathing secured to said side plate and posts, said side plate, posts and sheathing being spaced outwardly of said underframe, brackets secured to the lower ends of said posts, said brackets extending inwardly from said posts to said underframe and being secured thereto, and a longitudinally ex-

tending member spaced outwardly of said underframe and having a horizontal flange disposed below and in vertically overlapping engagement with said brackets, said member having an unstanding flange fastened to said posts and the lower margin of said sheathing, said longitudinally extending member being formed of a rolled section of the same width for varying inside widths of car.

10 7. A side wall structure for railway house cars comprising a side plate, posts secured to said side plate, metallic sheathing secured to said side plate and posts, connecting brackets secured to the lower ends of said posts, and a longitudinally extending member, said member having a flange disposed below and in vertically overlapping engagement with said brackets, said member having an upstanding flange secured to the posts and the lower margin of said sheathing.

15 8. A side wall structure for railway house cars comprising a side plate, posts secured to said side plate, metallic sheathing secured to said side plate and posts, connecting brackets having outer sections disposed below said posts, flanges extending upwardly from said outer sections, said flanges being secured to the lower ends of said posts, and a longitudinally extending member, said member having a flange disposed below and in vertically overlapping engagement with said brackets, said member having an upstanding flange secured to the posts and the lower margin of said sheathing.

20 9. As an article of manufacture a bracket for attaching a post of a side wall structure to a railway car underframe comprising a vertical underframe attaching flange, a horizontal flange extending from said vertical flange, a vertical reinforcing web for said horizontal flange extending from said vertical flange, a horizontal section 25 beyond said web for securing overlapping engagement of a horizontal flange of said side wall with the underside thereof, said section being adapted to lie below a post and having an upwardly extending post attaching flange, said section being of greater thickness than said horizontal flange and of sufficient cross sectional area to resist stresses imposed thereon by said post.

FRANK DITCHFIELD.
